UNITED STATES PATENT OFFICE

EDWARD J. CROWSON, OF FITCHBURG, MASSACHUSETTS

PAPER-MAKING MACHINE

Application filed September 10, 1928. Serial No. 304,926.

This invention relates to new and useful improvements in paper making machines, and more particularly to means for imparting translational bodily movement to a Fourdrinier wire engaging device, whereby this wire is continually and slowly moved from side to side transversely of the paper making machine to accomplish the very important function of preventing the wire from grooving the suction boxes and the deckle straps from imposing excessive wear upon the wire.

It is well known in the paper making art that the Fourdrinier wire continually runs over the same surfaces of the suction boxes; ordinary guides and other devices being provided to center the wire upon the machine, with the result that in a very short time after being placed in use, the wire wears objectionable ridges in the suction boxes and the deckle straps wear grooves in the wire, both of which contribute to the formation of objectionable lines in the paper, to say nothing of the expense involved in continually replacing the wire and planing the surfaces of the suction boxes smooth. It is, therefore, the principal object of this invention to provide means for continually and slowly moving the Fourdrinier wire from side to side so that the objectionable grooving of the suction boxes and excessive wear placed upon the wire by the deckle straps will be eliminated whereby perfect paper may be produced without the necessity of frequent replacements of the suction boxes and Fourdrinier wire.

Another object of the invention is to employ the usual guide roll for the accomplishment of these functions, and to impart to this roll translational bodily movement transversely of the paper making machine by means of a reversing and speed reducing mechanism operated by the guide roll itself.

A further object of the invention is to provide an automatic wire guide for engagement with an edge of the Fourdrinier wire, operating in conjunction with the translational movements of the guide roll in order to maintain the wire centered with respect to the roll, and subject to the direct influence of the translational movement of the guide roll.

Other objects and advantages of the in-

vention will become apparent during the course of the following description.

In the accompanying drawings forming a part of the application, and wherein like numerals are employed to designate like parts throughout the several views:

Figure 1 is a top plan of one end of a paper making machine with my improvements applied thereto.

Figure 2 is a side elevation of the same.

Figure 3 is an enlarged longitudinal vertical section taken through the reversing and speed reducing mechanism for imparting translational movement to the guide roll.

Figure 4 is an end elevation of the same, and

Figure 5 is a transverse vertical section through the same taken on the line 5—5 of Figure 3.

Referring now more particularly to the drawings, the numeral 6 designates the usual table of a Fourdrinier machine supported by the usual frame 7, below which are arranged the usual suction boxes 8, 9, 10 and 11, over which runs the usual Fourdrinier wire 12 which passes around the well known type of rotary suction box 13 and over the automatic guide roll 14 supported between the rotary suction box and the end of the frame 7. Other parts of the well known type of the paper making machine are illustrated, but as they form no part of the present invention, a description thereof is deemed unnecessary.

As stated in the objects of the invention, the principal object of the invention is to impart translational bodily movement to the automatic guide roll 14 of the paper making machine, and in order to do this, both bearings of the guide roll shaft 15 are mounted for sliding movement transversely of the Fourdrinier machine, as will now be described. One end of the guide roll shaft 15 has secured thereto a beveled gear 16 and is journaled in a bearing eye 17, which is loosely mounted upon the upper end of a stub shaft 18 of a reversing mechanism 19 to be pivoted on a vertical axis to swing in a horizontal plane while the reversing mechanism 19 is automatically moved back and

forth transversely of the machine in a manner which will be presently described. It will, therefore, be obvious that one end of the guide roll shaft 15 is both slidably and pivotally supported.

The other end of the guide roll shaft is indicated by the numeral 20, see Figure 2, and is journalled in a bearing mounted upon a slide 21 of the well known type of wire guide device, and which is capable of sliding longitudinally of the Fourdrinier wire upon a stand 22, which in the present instance, instead of being rigidly connected to the frame of the paper making machine, is dove-tailed for sliding movement transversely of the Fourdrinier wire and machine in a bracket 23 secured to the frame 7. This end of the guide roll shaft is connected to the well known type of wire guide device, such as shown in the patent to Gilbert and Nash, No. 694,368 patented March 4, 1902, and which includes a horse-shoe double pawl and ratchet mechanism 24 reciprocated vertically by the link mechanism 25 connecting the double pawl with the sliding block 21 and the end 20 of the guide roll shaft for swinging the guide roll 14 upon its pivot 18 whenever the Fourdrinier wire runs to one side or the other relative to the guide roll 14, in order to center the wire upon the roll in the well known manner. This automatic wire guide device also includes the well known type of double ratchet wheel 26 threaded upon a screw shaft mounted in the sliding stand 22 and connected to the block 21, and the connecting mechanism between the horse-shoe pawl and the guide pan 27, which engages one edge of the Fourdrinier wire as disclosed in the aforesaid patent in order that this automatic guide device will maintain the Fourdrinier wire centered with respect to its guide roll 14 whenever the wire moves relative to this roll.

The reversing mechanism which imparts translational bodily reciprocations to the guide roll transversely of the machine, is enclosed in a housing 28, which is dove-tailed for sliding movement transversely of the machine in a bracket 29 secured to the Fourdrinier frame, as shown in detail in Figure 4. This housing consists of an open ended housing having a removable top 30 bolted to the same and having a bearing 31 for the vertical stub shaft 18, the lower end of which reposes in a bearing 32 formed in the bottom of the housing so as to support the stub shaft for free rotation. A beveled gear 33 is keyed to this stub shaft on top of the cover 30, and meshes with the bevelled gear 16 of the guide roll shaft for imparting rotation to the stub shaft 18. Loosely mounted upon the stub shaft in vertical spaced relation are a pair of clutch gears 34 and 35, each of which is provided with a clutch element 36 for alternate engagement with a double

faced clutch element 37 splined upon the stub shaft 18 between the two gears 34 and 35. This clutch element 37 is alternatively moved into engagement with the clutch gears 34 and 35 by a trip mechanism consisting of a lever 38 secured to a transverse shaft or rod 39 journalled in the sides of the housing 28, and which is oscillated by a depending trip finger 40 secured to the shaft 39 and arranged to move along the side of the stand 29 between a pair of spaced abutment elements 41 and 42 projecting horizontally from the side of the stand 29. The two clutch gears 34 and 35 are constantly in mesh with opposite sides of a bevelled gear 43 secured to one end of a sleeve 44 rotatably mounted and supported by a pair of spaced bearing stands 45. These stands are removably mounted within the housing 28 by reason of their being provided on their bottoms with a projecting pin 46 adapted to be received in a socket 47 in the bottom of the housing 28, while the sides of these bearing stands are provided with laterally projecting lugs 48 adapted to be arranged in vertical ways 49 provided in opposite sides of the housing 28 and resting upon abutments 50. These bearing stands 45 are simply slipped downwardly into the housing with their lugs 48 moving through the grooves 49 until the pin 46 rests upon its seat in the bottom of the housing, and the lugs 48 rest upon the abutments 50.

Each of these bearing stands 45 is provided with an upwardly projecting stud 51 adapted to be received in a socket 52 formed in the cover plate 30 to rotatably mount reduction bevelled gears 53 and 54 upon vertical axes.

This speed reducing gearing involves a single tooth or finger 55 secured to the bevelled gear 43, and meshing with the bevelled gear 53. It also includes a second step in speed reduction, provided for by a large bevelled pinion 56 loosely mounted upon the sleeve 44 and meshing with the bevelled gear 53. This gear 56 is provided with a single tooth or finger 57, which is in mesh with the teeth of the bevelled pinion 54 so as to rotate the latter one tooth for every complete revolution of the gear 56.

The reversing mechanism housing 28 and guide roll 14 are given translational bodily movement by a screw arrangement, including a stationary horizontal screw shaft 58 which is supported and secured at one end by an upstanding arm 59 of the stand 29. The opposite end of the screw shaft is supported by its projection into the rotary sleeve 44. The connection between this screw shaft and the housing 28 is provided for by a bevelled gear 60 rotatably mounted upon the rotary sleeve 44 and constantly arranged in mesh with the reducing gear 54. This bevelled gear 60 is provided with a nut formation 61 which cooperates with the threads of the screw shaft 58 for moving the housing 28 back and forth.

To accomplish this, the bevelled gear 60, while being freely rotatable independently of the rotary sleeve 44, is connected therewith so as to move the latter whenever the nut 61 moves longitudinally of the screw shaft 58.

In operation, movement of the Fourdrinier wire 12 imparts rotation to the guide roll 14 and shaft 15, which rotates the gears 16 and 33, and, consequently, the stub shaft 18 and 10 double clutch element 37 which is in engagement with one or the other of the clutch elements 36 of the clutch gears 34 and 35, depending upon which trip element has last engaged the trip lever 40. This will cause 15 rotation of the bevelled gear 43 and will cause the tooth 55 of this gear to turn the bevelled gear 53 one tooth for every one revolution of the gear 43. This, in turn, will step the speed down through the gear 56, tooth 20 57, and gear 54 to cause slow rotation of the gear 60, which having the nut formation thereon, moves along the screw shaft 58 slowly, thereby moving the guide roll 14 bodily in one direction transversely of the machine 25 to carry the Fourdrinier wire 12 sidewise with it and thereby move this wire transversely across the suction boxes. When the trip lever 40 engages its trip element 41 or 42, depending upon the direction of movement 30 of the reversing mechanism, the double clutch element 37 will be moved into engagement with the other clutch gear to reverse the direction of rotation of the gear 43, and, consequently, the gear 60 which moves the 35 housing 28 in the opposite direction, together with the guide roll 14. This carries the Fourdrinier wire in the opposite direction transversely of the machine and across the faces of the suction boxes. Consequently, it 40 will be seen that the wire is not permitted to move continually in one path across the suction boxes, and, accordingly, they will not become grooved with the detrimental effects upon the paper being made by the machine.

45 Should the Fourdrinier wire 12 move from one side to the other relative to the guide roll 14, the automatic wire guide device 27 will be moved one way or the other depending upon the direction of movement of the wire 50 relative to the roll and will move the proper pawl into engagement with the ratchet wheel 26, so that this pawl will rotate the ratchet wheel in the proper direction due to the horseshoe pawl being connected through the linkage 55 with the guide roll, thereby causing the double ratchet wheel 26 and block 21 to move in a direction to swing the guide roll upon its pivot 18 to cause the wire to move back to its centralized position upon the guide 60 roll 14. As explained in the Gilbert and Nash patent, referred to above, the automatic guide device will check the movement of the Fourdrinier wire and move it back to its centralized position upon the guide roll in which- 65 ever direction the wire may move upon the

roll, and as long as the Fourdrinier wire remains in its centralized position upon the guide roll 14, the automatic wire guide 27 will not be called into operation and will not be affected by the translational bodily movements of the guide roll effected through the reversing mechanism.

70 It will be understood that various changes in the size, shape and arrangement of parts may be resorted to without departing from the spirit of the invention or the scope of the appended claims.

I claim:

1. A Fourdrinier machine having a translationally movable device operated by the wire, and means whereby said device by its 80 operation continually shifts the wire from side to side.

2. A Fourdrinier machine having a translationally movable device rotated by the wire, and means whereby said device by its movement continually shifts the wire from side to side.

85 3. A Fourdrinier machine having a wire guide roll, and means for imparting translational bodily movement to said roll to cause lateral shifting movement of the wire.

90 4. A Fourdrinier machine having a wire guide roll, and means for imparting reciprocatory translational bodily movement to said roll transversely of the machine to cause lateral shifting movement of the wire.

95 5. A Fourdrinier machine having a wire guide roll mounted for translational bodily movement to cause lateral shifting movement of the wire, and means operated by the rotation of said roll for continually moving the same so as to shift the wire continually from side to side.

100 6. A Fourdrinier machine having a wire guide roll, means for imparting translational bodily movement to said roll and means to cause the roll to swing to cause lateral shifting movement of the wire relative to the guide roll.

105 7. A Fourdrinier machine having a wire guide roll mounted for translational bodily movement to cause lateral shifting movement of the wire with said roll, said roll being also mounted for swinging movement to center the wire thereon, and means operated by the rotation of said roll for continually bodily moving the same so as to shift the wire continually from side to side.

110 8. A Fourdrinier machine having a wire guide roll mounted for translational bodily movement to cause lateral shifting movement of the wire with said roll, said roll being also mounted for swinging movement to center the wire thereon, means operated by the rotation of said roll for continually bodily moving the same so as to shift the wire continually from side to side, and means operated by relative movement of the wire and

115 roll to center the wire on said roll.

9. A Fourdrinier machine having a wire guide roll mounted for translational bodily movement to cause lateral shifting movement of the wire from side to side, and a reversing mechanism for bodily moving said roll. 70
10. A Fourdrinier machine having a wire guide roll with its bearings mounted for sliding movement to cause translational bodily movement of said roll, and means operated by said roll for effecting bodily reciprocatory movement of said roll from side to side. 75
11. A Fourdrinier machine having a wire guide roll with its bearings mounted for sliding movement to cause translational bodily movement of said roll, and a reversing mechanism operated by said roll for effecting bodily reciprocatory movement of said roll from side to side. 80
12. A Fourdrinier machine having a wire guide rod with its bearings mounted for sliding movement to cause translational bodily movement of said roll, a reversing mechanism operated by said roll for effecting bodily reciprocatory movement of said roll from side to side, and a speed reducing mechanism associated with said reversing mechanism. 85
13. A Fourdrinier machine having a wire guide roll with its bearings mounted for sliding movement to cause translational bodily movement of said roll, a worm, and a reversing mechanism connected to one of said sliding bearings and associated with said worm and operated by said wire guide roll to cause reciprocation of said bearings and roll. 90
14. A Fourdrinier machine having a rotary and reciprocatory shaft with a wire guide roll secured thereto, a reversing mechanism including a stationary screw shaft and a nut operable thereon, means for imparting reciprocatory movement from the nut to said roll shaft, means for alternately rotating said nut in opposite directions, and trip means for actuating said last named means. 95
15. A Fourdrinier machine having a rotary and reciprocatory shaft with a wire guide roll secured thereto, a reversing mechanism including a reciprocatory casing having connection with said shaft, a stub shaft mounted in said casing and driven by said roll shaft, a pair of clutch gears freely rotatable upon said stub shaft, a clutch element splined upon said stub shaft and alternately engageable with said clutch gears, a trip device connected to said clutch element, a screw gear mounted in said casing and engaging said clutch gears, and a stationary screw shaft engaging said screw gear. 100
16. A Fourdrinier machine having a rotary and reciprocatory drive shaft with a wire guide roll secured thereto, a reversing mechanism including a shaft to which one end of said drive shaft is pivoted for effect- 105
